METHOD OF AND APPARATUS FOR FEEDING FOIL STRIP AND THE LIKE

Edward N. Trump and Albert D. Hallett,
Syracuse, N. Y.

Application June 1, 1937, Serial No. 145,906

12 Claims. (Cl. 93—60)

This invention appertains to an improved method and apparatus for feeding strips or sheet material, and more particularly, has reference to the feeding of foil strips in the manufacture of over-all bottle caps and the like.

In the manufacture of foil bottle caps, it has been the customary practice in the past to intermittently feed a strip of foil between coactive, relatively movable dies which serve to successively 10 cut circular blanks from the strip and then form the same into cap form. As far as we are aware, the foil strip has heretofore always been fed by a pulling action on the strip. Consequently, the foil strip must be substantially wider than the circular blanks which are cut out of the same. As a result, considerable scrap remains after the blanks have been cut from the strip and the caps formed from the blanks. For example, to make bottle caps of standard size for milk bottles, it 20 has been customary to employ a foil strip at least four and one-quarter inches in width, from which circular blanks or discs four inches in diameter are successively cut and formed into caps. This leaves a continuous length of scrap material 25 which is composed of a series of generally triangular shaped segments intermediate each successive cut, which segments are united together at the margins of the strip by a marginal web approximately one-eighth of an inch wide at its narrowest point at each edge of the foil strip. In the case of a four and one-quarter inch strip from which four inch blanks are cut, the scrap foil amounts to approximately twenty-eight percent of the strip. The scrap, of course, will run 30 higher in cases where the blanks are cut from strips wider than that above mentioned. In following the old practice, it is impractical to use narrower strips of foil, because this would result in frequent severance of the scrap due to the tension on the same, having in mind that the feeding is accomplished by a pulling action on the foil exerted by the usual feed rollers which are located at the side of the dies opposite to the source of strip supply.

45 According to the present invention, the feeding of the foil strip is accomplished by a pushing action, such action being obtained by arranging the feed rollers or other equivalent feeding instrumentalities in advance of the blank cutting and 50 cap forming dies. In other words, the strip feeding instrumentalities are arranged at the same side of the dies as the source of strip supply. As a result, complete severance of the strip may be effected each time a blank is cut from the strip, 55 without interfering with the feeding action.

Moreover, the scrap material may be more readily separated from the formed caps and disposed of in such manner that the caps may be discharged from the machine and suitably collected for use without interference by the scrap material. 5

As a specific example of the practice of our improved invention, foil strip three and seven-eighths inches wide may be employed in making the same caps formerly made from strip four and one-quarter inches wide or wider. From this narrower strip, four inch discs are cut and formed into caps in the usual manner, and as a result, the foil strip will be completely severed each time a blank is cut out from the strip, leaving small generally triangular shaped scrap segments, which are separated instead of joined together as formerly. Suitable instrumentalities are preferably provided for disposing of the separated scrap pieces during the formation of the caps, the scrap being preferably discharged from the machine in such manner that they can be collected separately from the finished caps. It will readily be apparent that we are able to utilize narrower foil strips than has heretofore been possible in making a cap of predetermined size, and to materially reduce the amount of scrap or waste material which is left after the caps are formed. In the specific example given above, as 20 illustrative of the present invention, the scrap material amounts to only approximately eighteen percent of the strip, thus resulting in a saving of something over ten percent, having in mind the use of narrower strips as well as the complete severance of the strip each time a cap blank is 25 cut therefrom. Such a saving is very important from the standpoint of economy of manufacture of foil caps, and in addition to this greater economy, we are able to materially improve the efficiency of the cap making machines and to provide other improved features which are very desirable and which will hereinafter be more specifically referred to. 30

The primary object of the invention, therefore, is to provide an improved method and apparatus by which the scrap or waste material in the manufacture of bottle caps and the like is reduced to a minimum and to a degree far below that which formerly was obtained. 45

Another important object of the invention is to provide an improved method and means for feeding foil strips and the like, characterized by the utilization of a pushing action upon the strip, as distinguished from a pulling action. 50

Still another object of the invention is the pro- 55

vision of a novel and improved method and means for reinforcing or stiffening of the foil strips so that the same can be more readily adapted to the utilization of a pushing type of feeding action. To this end, the foil strip is preferably corrugated or ribbed in the direction of its feed, thus resisting buckling of the strip during the feeding action, and the pushing out of the finished cap.

10 A further object of the invention is to provide an improved feeding mechanism by which the foil strip may be intermittently advanced in timed relation to the operation of the cap forming dies of the cap making machine, the mechanism being preferably of such construction that the foil strip is relieved from excessive strains tending to tear the same.

15 Other and further objects and advantages will be hereinafter described, and the novel features thereof defined by the appended claims.

20 In the drawings:—

Figure 1 is a view in side elevation of a typical machine for making foil bottle caps of the over-all type, and having our invention incorporated therein, certain of the parts of the machine being broken away and shown in section;

25 Figure 2 is an end elevation of the machine shown in Figure 1, as observed towards the cap discharge end, certain parts of the machine being broken away to more clearly disclose the upper reciprocal cap forming die assembly and the scrap punches associated therewith;

30 Figure 3 is a horizontal sectional view, taken through the machine at a point above the bed thereof, with certain of the superstructure omitted, and more particularly illustrating certain parts of the foil feeding and guiding instrumentalities;

35 Figure 4 is a fragmentary vertical sectional view, illustrating in a somewhat diagrammatic manner the cooperative relationship of the foil feeding instrumentalities with the cap forming dies which are shown in more complete detail;

40 Figure 5 is a fragmentary top plan view of the foil feeding rollers and a fragmentary length of foil in the stage just following the completion of the formation of a cap, and particularly illustrating the blanketing and cap forming operations on the foil, the dotted lines illustrating the scrap material which remains after the cutting of the blank and formation of the same into the finished cap which is shown in top plan;

45 Figure 6 is a fragmentary detail vertical sectional view illustrating the scrap dies or receivers into which the scrap material is forced by means of the punches shown in elevation, the scrap being shown in full lines just prior to being engaged by the punches, and the dotted lines illustrating the action of the punches in forcing the scrap into the dies from which they are ultimately conducted to a suitable point of discharge separately from the finished caps;

50 Figure 7 is a top plan view of the foil spool or reel and its support by which the same is mounted on the cap making machine;

55 Figure 8 is an enlarged fragmentary detail sectional view of the complementary foil feeding rollers between which the foil strip passes in advance of the cap forming dies, and which serve to corrugate the strip preferably adjacent to each marginal edge thereof so as to stiffen the foil and prevent the same from buckling during its feeding action;

60 Figure 9 is a fragmentary detail view of the ratchet and pawl instrumentalities and their

rack and pinion driving devices which serve to actuate the foil feeding rollers;

65 Figure 10 is an enlarged fragmentary detail sectional view of one of the foil strip guides which also serves to automatically operate a suitable safety control such as an electric switch whereby the cap making machine will be automatically shut down or stopped if the foil strip should break during operation of the machine; and

70 Figure 11 is an enlarged detail sectional view of a finished foil cap of one type for which the machine herein shown is employed, as illustrative of one practical application of our invention.

75 Like reference characters designate corresponding parts in the several figures of the drawings.

80 As previously mentioned, our invention is particularly applicable to the making of over-all bottle caps, and the following description will be primarily directed thereto. However, it is to be understood that our invention is not limited to this field, nor to the particular type of cap making machine hereinafter referred to by way of illustration of the general features of the invention.

85 In Figure 11, there is shown an over-all bottle cap of a well known type, said cap being preferably made of foil and being generally designated 1. In the manufacture of such caps, it has been the practice to cut out circular foil blanks from a strip or sheet of foil (aluminum foil being preferred), and then to form the blank by bending its marginal portions downwardly to provide an annular skirt 2. After the formation of the skirt 2, the central portion of the blank is depressed, as at 3, into a generally cup-shaped form, this depressed portion being adapted to be received within the mouth of the bottle when the cap is applied thereto. The rim 4 of the cap 1 generally conforms to the shape of the bead which is ordinarily provided at the mouth of the bottle, and the skirt 2 extends over and about the outer face of the bead so that when the cap is applied to the bottle and the central cup-shaped portion 3 is expanded into close contact with the inner wall of the bottle mouth and the skirt is constricted or crimped about the outer face of the bead and the neck of the bottle, an effective and sanitary seal is established between the cap and the bottle. The rim 4 is preferably corrugated, as at 5, and these corrugations serve to stiffen the same and to allow for expansion of the central cup 3 after application of the cap to the bottle. The skirt 2 is likewise preferably wrinkled or rumpled about its circumference during the formation of the cap.

90 The means for forming the cap 1 is best seen in Figure 4 of the drawings, and comprises, in general, an upper reciprocal die 6, and a coactive stationary lower die 7. The construction and operation of the dies is such that when a strip of foil 8 is fed between the dies 6 and 7, and the upper die 6 is moved in a downward direction into engagement therewith, the strip of foil is first clamped by an annular clamping member 9, which, in this case, is shown as a heavy member carried by and axially movable relatively to the die assembly 6 so that its weight will exert a clamping pressure on the foil strip when lowered into engagement therewith, and before the forming of the cap begins. Further downward movement of the upper die 6 results in the cutting of a circular disc or blank from the foil strip 8, and formation of the blank into the finished cap, as shown in Figure 11. This is all

accomplished during one stroke of the upper die 6.

A more detailed explanation of the construction and operation of the dies, and the construction and formation of the cap will be found in the applications of Charles A. MacCordy, Serial Nos. 682,474 (now Patent No. 2,076,906), 704,899 (now issued into Patent No. 2,082,167), 13,727 and 131,096, the latter two applications being divisions of the first. Reference will now be had to Figures 1, 2 and 3 of the drawings, by way of explanation of the application of our present invention to the manufacture of caps such as those forming the subjects matter of the applications above referred to.

10 generally designates the base of a typical cap making machine in which the dies 6 and 7 of Figure 4 are embodied. Extending vertically upwardly through the bed or table 11 of the base 10, and reciprocable therein, there is provided a pair of guide bars 12, upon which is mounted a vertically reciprocal cross-head 13, to which the upper die 6 is suitably affixed for movement in an upward and downward direction responsive to reciprocation of the cross-head. Any suitable means may be employed to impart reciprocal motion to the cross-head, and consequently, to the die 6, and we have illustrated herein, by way of example, a practical means for this purpose which has been found eminently satisfactory. As best seen in Figure 2, the cross-head 13 is provided with lateral extensions at its opposite ends, upon which are rotatably mounted, respectively, roller members 14 which are disposed within cam tracks 15' formed in the inner faces of a pair of rotary cams 15 arranged at opposite sides of the machine, respectively. These cams 15 are fixedly mounted upon a transversely disposed shaft 16 which is adapted to be driven by any suitable source of power, such as an electric motor (not shown). As will be perfectly obvious, the cam tracks 15' which cooperate with the rollers 14 are so constructed and arranged that upon rotation of the shaft 16 and cams 15, motion alternately in an upward and downward direction will be imparted to the cross-head 13 and die unit 6, according to the requirements more particularly set forth in the prior applications previously referred to, to cause the die 6 to perform its cap blanking and forming functions in cooperation with the stationary die unit 7 which is suitably mounted in the bed of the machine in coaxial relation to the upper die 6.

55 Mounted at one side of the dies is a spool or reel 17, upon which the foil 8 is wound to provide a source of foil strip supply, the spool being suitably supported as by means of the brackets 18 which are attached to the base 10 of the cap making machine. In feeding the strip 8 from the spool 17 to the dies, the foil is trained over a roll 19, having guide flanges at its opposite ends, which is adapted to have a limited oscillating movement in a vertical plane, and thence the foil passes under a tension roll 20, from which it leads to a pair of feed rolls 21 and 22 which are arranged one above the other with their contiguous or tangential surfaces disposed at about, or slightly above, the upper face of the table or bed of the machine across which the 70 foil is fed from the feed rolls to the dies. Suitable means is provided for positively and intermittently actuating the feed rolls 21 and 22 in timed relation to the reciprocal movement of the upper die assembly 6, and such means will be now 75 more particularly described.

Keyed or otherwise secured to one end of the cam driving shaft 16, we provide a crank 23. This crank 23 is provided with a crank pin 24 preferably eccentrically mounted to allow adjustment of movement of roll 19, on which is pivotally mounted a cross-head or guide block 25, this cross-head 25 in turn being slidably mounted upon a pair of spaced bars or rods 26 which extend through suitable openings in the cross-head 25 at opposite sides of the crank pin 24. The bars 26 are adjustably secured at their opposite ends to suitable spacing means or head blocks 27 and 28 respectively, the latter being pivotally mounted, as at 29, on a convenient part of the frame, such as 30, which forms a part 15 of the superstructure of the machine. Integral- 20 ly formed with or otherwise attached to the head block 28, there is provided an arm 31, which extends towards the side of the pivotal axis 29 opposite to the side on which the bars 26 are dis- 25 posed. The arm 31 is yieldably interconnected to a link 32 by means of a coil spring 33, one end of which is secured to the laterally offset end 34 of the link 32, and the other end of which is secured to a stud or pin 35 which is carried by 30 the free extremity of the arm 31. The lower end of the link 32 is pivotally connected, as at 36, to one arm 37 of a bell crank lever 38, which is pivotally mounted, as at 39, on the frame 30. The other arm 40 of the bell crank lever 38 ro- 35 tatably supports the roller 19 over which the foil strip 8 is trained, as previously mentioned.

The head block 27 is pivotally connected, as at 41, to one end of a link 42 which serves to inter- 40 connect the block 27 with a reciprocatable rack 43, the latter being pivotally connected, as at 44, to the opposite end of the link 42. The rack 43 is preferably provided with a housing 45 which serves to enclose the same, and in which the rack is slideable. The teeth 46 on the face of the 45 rack 43 are adapted to mesh with the teeth 47 of a pinion 48 which is loosely mounted on the end of a shaft 49, which extends laterally from one end of one of the feed rollers, and more particularly, the lower feed roller 22. Mounted 50 on the pinion 48, we provide one or more pawls 50 which are adapted to cooperate with a toothed ratchet wheel 51 which is fixedly mounted on the end of the shaft 49. As shown in the drawings, two pawls 50 arranged at diametrically opposite points are preferably provided, and it will be understood that these pawls are adapted to be normally urged into engagement with the teeth of the ratchet wheel 51 by any suitable means such as springs (see Fig. 9), so that when the 55 rack 43 is reciprocated in one direction, causing the pinion 48 to be rotated in a clockwise direction, as viewed in Figure 1, the motion of the rack will be transmitted to the lower feed roll 22, thereby causing the same to also be rotated in a clockwise direction. On the other hand, when the motion of the rack 43 is reversed, the rotation of the pinion 48 will likewise be reversed, but no motion will be imparted to the feed roll 22 by reason of the fact that under this condition, the pawls 50 will freely ride over the teeth of the ratchet wheel 51, with which they are adapt- 60 ed to cooperate for transmitting motion to the feed roll 22 when the rack 43 is moved in one direction only.

65 Preferably, the feed rolls 21 and 22 are inter- 70 connected by suitable meshed pinions 52, as will be best understood from reference to Figure 3, so that both feed rolls will be positively driven in opposite directions by the ratchet mechanism just 75

described. However, it is to be understood that it is not essential that both rolls be positively driven since satisfactory results may be obtained by positively driving only one of the feed rolls, as for example, the roll 22. The upper feed roll 21 is preferably mounted so as to permit adjustment of the same towards and away from the roll 22 for the purpose of providing the proper frictional contact between the rolls and the foil strip 8 which is adapted to pass therebetween, and, if desired, provision may be made for releasing the upper feed roll 21 so that it will be normally urged upwardly away from the lower roll 22 for the purpose of facilitating the initial introduction of the foil strip 8 between the rolls, or for adjusting the foil strip in the machine at the beginning or during operation thereof. The releasing instrumentalities just referred to are preferably of such character that the adjustable roll may be locked in adjusted position after the proper adjustment has been effected. These instrumentalities are generally designated 53 in the drawings, and since the specific details thereof are not essential to an understanding of the main invention to which this application is directed, they have not been particularly shown, and need not be further described.

Referring now to Figures 5 and 8 of the drawings, it will be observed that the feed rolls 21 and 22 are preferably knurled or otherwise roughened intermediate their ends, as at 54, so as to afford firm engagement with the foil strip 8 without appreciable slippage. The lower roll 22 is provided adjacent each end with an annular rib 55 having a generally arcuate surface which is raised slightly above the outer surface of the main body of the roll. The other roll 21 is provided adjacent each of its opposite ends with a shallow annular groove or recess 56, complementary to the ribs 55. Thus when the foil strip 8 is fed through the feed rolls 21 and 22, the foil will be ribbed or corrugated, as at 57, adjacent to each marginal edge thereof, the corrugations 57 extending lengthwise of the foil strip 8 and serving to stiffen the same against buckling. Consequently, as the foil strip 8 is pushed across the bed or table 11 of the machine towards the dies 6, 7, by means of the feed rollers 21 and 22, the foil will lie flat. Without this reinforcement or stiffening of the foil just referred to, the foil strip would very likely buckle, and hence would not become accurately positioned with relation to the dies 6, 7.

In order to prevent the foil from being unrolled too fast from the spool or reel 17, we preferably provide a suitable drag or brake action on the foil, as for example, by providing suitable adjustable friction brake instrumentalities, generally designated 58. As best seen in Figures 1 and 7, the drag or brake device acts upon a suitable friction bearing surface 59 on one face of the spool, and the degree of braking or drag action can be adjusted by suitably manipulating one or more set screws which are mounted in one of the reel or spool supports 18. The action of the brake device should be readily understood from the foregoing general description, taken in conjunction with the drawings, and since the action of the same is well known to those skilled in the art, further explanation and illustration thereof is unnecessary.

Considering now the timed relation of the foil feed respecting the cap blanking and forming action of the dies, it will be observed that the normal arrangement of the actuating means for

the feed rolls 21, 22, which includes the crank 23, crank pin 24, slide block 25, the bars or rods 26, the head block 27, link 42, rack and pinion 43, 48, and the pawls and ratchet 50, 51, is such that on the upward stroke of the cross-head 13, which carries the upper die assembly 6, the rack 43 is actuated in such direction as to impart a driving action to the feed rolls, thereby causing a predetermined length of the foil strip 8 to be fed towards the dies. The amount of foil fed during each intermittent feed stroke of the rack 43 is preferably equal to the diameter of the blank which is to be cut by the dies preliminary to forming the blank into its final cap shape. Accordingly, the successive blanks will be cut from the foil strip 8 without leaving any scrap at the center of the strip between contiguous blank cuts. On the other hand, this degree of accuracy is not absolutely essential, as will hereinafter become more apparent. Variation in the linear travel of the foil strip 8 during any single feed stroke of the rack 43 may be obtained by an adjustment of the throw of the crank arm 23 or otherwise, as will be obvious from the drawings. The feeding action of the feed rolls 21, 22 may take place during the upward stroke of the upper die assembly 6, as previously mentioned, or if desired, it may take place at the beginning of the downward stroke of the die, or partly during the upward stroke and partly during the downward stroke. It is important, however, that the feed of the required length of foil strip be completed before the clamping member 8, which is carried by the upper die 6, comes into engagement with the foil on the down-stroke of the die assembly.

Between the feed rollers 21, 22 and the dies, we preferably provide spaced resilient guides 60 which are fixed to the bed or table 11 at their ends adjacent to the feed rollers so as to receive the marginal edges of the foil strip 8 therein, and so as to permit flexing movement of their free extremities towards and away from the bed or table adjacent to the dies. As seen in Figure 3, the guides 60 extend from a point closely adjacent to the feed rollers, towards and partially under clamping member 8, which presses them down, returning by their inherent resiliency as member 8 is raised, to a point which guides the foil to the center of height of the cap, so the foil will push the cap out from under the die 6 and the annular clamping member 8.

Carried by the upper die assembly 6, or otherwise suitably mounted upon the reciprocal cross-head 13 so as to be shiftable upwardly and downwardly along with the upper die assembly, we provide a pair of scrap punches or plungers 61, the same being positioned in spaced relation to each other a distance somewhat less than the transverse width of the foil strip 8. Cooperative female dies or receivers 62 are arranged in register with the plungers 61 in the bed or table 11 of the machine, and these dies 62 communicate with a suitably arranged discharge chute 63, as will be best understood from reference to Figures 1 and 6. It will be observed that the dies 62 are substantially larger than the plungers 61. The purpose of these dies 61, 62 is to separate the scrap foil from the finished caps and to convey the scrap to a suitably convenient point of discharge 70 where the scrap may be collected and disposed of as desired. As shown in Figure 5, the foil scrap will have the form of relatively small, generally triangular shaped pieces, designated 64, these pieces being arranged one at each side of 75

the median of the foil strip 8, and are the result of cutting a generally circular blank from the strip 8 on the lines 65, 66 and 67. As indicated in Figure 5, the cutting of the blank preferably completely severs the strip 8, and separates the scrap pieces 64, as shown in dotted lines in this figure. The scrap pieces 64 are pushed into the dies 62 by the plungers 61 preferably simultaneously with or shortly after the cap blank is cut out of the strip 8, and by reason of the fact that the dies 62 are larger than the punches or dies 61, the scrap pieces 64 will be forced downwardly into the dies 62, as illustrated in dotted lines in Figure 6. It will be understood that the action of the punches 61 to get rid of the scrap is intermittent, and corresponds to the intermittent cutting of successive cap blanks from the foil strip 8, each of which blanks is shaped into the form of a finished cap, designated 1, before a succeeding blank is cut. The action of the machine is relatively rapid so that the making of the caps may be said to be accomplished by a substantially continuous process at the rate of fifty to one hundred caps per minute. This rate may be varied slower or faster, as desired. Upon completion of a single cap, it is pushed towards the discharge end of the machine by the forward edge of the foil strip 8 during the succeeding advancement of the foil strip between the dies preparatory to forming a succeeding cap. The caps are preferably discharged at the end of the machine through a chute 68, which serves to direct the same to a convenient point for collection or packaging of the caps preparatory to distribution for use. As previously mentioned, the discharge of the finished caps is effected by the advancement of the foil strip 8, which pushes the previously finished cap towards the discharge chute 68, as will be understood from reference to Figure 4.

As a safety feature, we preferably provide a means controlled by the foil strip 8 for automatically stopping the machine in the event of breakage of the foil strip during operation of the machine. In Figures 1 and 10, we have shown a relatively simple device which is eminently suited for this purpose, although it is to be understood that we do not wish to be limited to the specific construction shown and now to be described. It will be observed that the roller 28, under which the foil strip 8 passes, and which is disposed intermediate the roller 19 and the feed rolls 21, 22, is mounted upon a pivotal arm 69 which is pivotally mounted, as at 70, at any convenient point on the frame of the machine. This arm 69 is normally urged in a counter-clockwise direction, as viewed in Figures 1 and 10, by means of a tension spring 71, which has one end connected with the lower extremity of the arm 69, as seen in Figure 10, and its other end fixed to a stationary part of the machine. The arm 69 has fixedly mounted thereon a mercury switch, generally designated 72, which may be of conventional construction, the switch being arranged in circuit with the electric motor which serves to drive the machine. When the arm 69 is positioned, as shown in full lines in Figure 10, the mercury in the switch 72 submerges the electrical contacts, and closes the electrical circuit to the motor through the conductors 73, so as to condition the motor for operation to drive the machine. The arm 69 and switch unit 72 are maintained in this operative condition by the foil strip 8, so long as the foil strip is unbroken. However, if the foil strip should break, as indicated in dotted lines in

Figure 10, the spring 71 will urge the arm 69 and the switch unit 72 to their dotted line positions shown in this figure, thereby causing the mercury in the switch unit to run to the bottom of the switch, resulting in opening the electrical circuit. In so opening the electrical circuit, the motor (not shown) will stop, and operation of the machine will be discontinued until the automatic control mechanism is restored to its normal operative position.

Reverse movement of the foil during the return stroke of the rack 45 is prevented by adjusting the friction brake instrumentalities 58, 59 so that the drag on the foil is greater than the frictional engagement of the pawls 50, 51 with the ratchet wheel 51 as they ride over the teeth of the ratchet wheel.

The method of constructing bottle caps from foil strip, and the means for practicing such method should be readily understood from the foregoing description, and may be briefly summarized as follows: The strip 8 is intermittently fed from a suitable source of supply by means of the feed rollers 21, 22 between which the strip 8 passes, and is advanced towards the dies by a pushing action imparted to the strip.

During the feeding of the strip 8, it is suitably stiffened or reinforced by corrugating the same lengthwise, as at 51, to afford sufficient stiffness to prevent the strip from buckling. Actuation of the feed rolls 21, 22 is effected by the pawl and ratchet means 50, 51 which in turn are operated by the reciprocal rack 43 which is driven in timed relation to the reciprocal die assembly 6. When the forward end of the strip 8 has been advanced so as to lie intermediate the coactive dies 6 and 7, movement of the strip is discontinued, and it is initially engaged by the clamping member 9 which is carried by the upper die assembly. This clamping member 9 rests upon the foil when the upper die assembly approaches the lower die, so as to hold the same flat while the cap blank is being cut and formed into the finished cap as the upper die assembly continues its downward movement. If desired, a spring 45 may be employed to yieldably urge the clamping member 9 against the foil so as to exert a yieldable clamping pressure thereon, as more particularly described in Patent No. 2,076,906, hereinbefore referred to. By making the member 9 sufficiently heavy to exert a clamping pressure on the foil by its own weight, as shown in Figures 1 and 4 of the present application, the spring just referred to may be omitted.

The member 9 strips the disc of foil from the punch and also actuates the ejector sleeve in the lower die 7 by a connection between them (not shown) through a slot to insure ejection of the cap.

The blanking punch presses the foil into the movable plate of the lower die assembly and scores the blank so that the folds lap over one another to form a triple thickness of the edge of the skirt to increase its stiffness. Continued downward movement of the upper die assembly, which has axial movement relatively to the member 9, cuts the cap blank from the foil strip 8 along the lines 65, 66, 67, as seen in Figure 5. The width of the strip 8 is preferably slightly less than the diameter of the die so that the strip is completely severed and the triangular-shaped scrap pieces 64 are cut free from the strip and are pushed down by the plungers 61 into the dies 62 as or shortly after the blank is cut. After cutting of the blank, continued downward move-

ment of the upper die assembly 6 forms the blank into the finished cap 1.

During the blanking and forming of the cap, and while the clamping member 8 is holding the foil by the clamping pressure thereon, the roller 19 over which the foil strip 8 is trained is rocked upwardly, thereby drawing some of the foil from the reel so as to enable the foil to be subsequently advanced by the feed rollers 21, 22 without the likelihood of tearing the foil, having in mind that the friction brake or drag instrumentalities 58 normally exert a drag on the foil strip to prevent the same from unrolling from the spool or reel 17 too fast. Having shifted the roll 19 upwardly to draw some of the foil from the spool or reel 17, the upper die assembly 6 moves upwardly, and picks up the clamping member 8 so as to carry the latter upwardly with it, thereby freeing the foil strip 8 and conditioning the same for further advancement towards the dies. The roller 19 is now rocked downwardly, and during or after the downward motion of this roller, the feed rolls 21, 22 are actuated to feed a predetermined length of the foil strip between the dies, preparatory to cutting and forming the next cap by a repetition of the cycle of operations just described. Of course, the friction of the brake on the supply spool 17 should be greater than the force exerted by the spring 11 on the automatic control which includes the guide roller 20, thereby keeping the arm 60 from swinging to the dotted line position shown in Figure 10 when the feed ceases. As the strip advances between the dies, it pushes the finished cap which was previously formed, in the direction of the arrow in Figure 4, causing the cap to be discharged from the machine. The scrap pieces 64, which are pushed down into the dies 62 by the punches 61, are discharged from the machine separately from the finished caps, preferably passing through a chute 63 from which the scrap may drop into a suitable receptacle for collection of the same until they may be conveniently disposed of.

By reason of the fact that we prefer to employ foil strip which is slightly narrower than the cap blank, thereby resulting in the complete severance of the strip and the separation of the relatively small scrap pieces, we are able to effect material savings in the manufacture of the caps. The same principles disclosed herein may be employed in the manufacture of articles other than bottle caps, so it is to be understood that we do not wish to be limited to the field of bottle cap manufacture. In the case of foil bottle caps, the invention is particularly important because of the expense of the foil, but the saving effected by the invention would be still present and in the same proportion over the old practices regardless of the nature of the specific material employed. While the specific details have been herein shown and described, the invention is not confined thereto, as changes and alterations may be made without departing from the spirit thereof as defined by the appended claims.

Having thus described our invention, what we claim as new and desire to secure by Letters Patent is—

1. In apparatus of the class described which includes relatively movable die members, pushing means for feeding a strip of material between said die members, and means forming a part of said pushing means for stiffening said strip material during feeding of the same, whereby to prevent the strip from buckling.

2. In apparatus of the class described which

includes relatively movable die members, cooperative feed rolls for feeding a strip of material between said die members, and means for corrugating said strip material lengthwise during feeding of the same, whereby to prevent buckling of the strip, said corrugating means comprising annular ribs formed on one of said feed rolls adjacent to its opposite ends, and the cooperating feed roll having annular grooves formed therein complementary to said ribs.

3. In apparatus of the class described which includes coactive relatively movable die members, a source of foil strip supply, pushing means for intermittently advancing said foil strip between said dies, means carried by one of said dies for initially engaging the foil strip so as to exert a clamping pressure upon the same, means operable after engagement of said foil clamping means with the foil strip for cutting a circular blank from said strip, the diameter of which is at least equal to the width of the foil strip, thereby forming substantially triangular shaped scrap pieces at the end of said strip, and means for separating said scrap pieces from the blank and for displacing the same from the path of the strip as the blank is formed by the dies into an article of predetermined shape, whereby the finished article may be discharged from the apparatus separately from the scrap.

4. Apparatus as claimed in claim 3, in combination with means engageable with the foil strip for withdrawing a predetermined length of foil from the source of supply while the foil clamping means is engaged with the foil.

5. Apparatus as claimed in claim 3, wherein the scrap separating means comprises cooperative relatively movable scrap-engaging dies operable in timed relation to the blank-forming dies to displace the scrap from the path of feeding movement of the foil strip.

6. In apparatus of the class described, which includes coactive die members, one of which is reciprocable towards and away from the other, and means for reciprocating the same, a source of strip supply positioned at one side of said die members, a pair of feed rolls interposed between the source of strip supply and die members and adapted to intermittently feed the strip with a pushing movement towards the die members, means positioned between the source of strip supply and feed rolls and about which the strip is adapted to be trained for withdrawing a length of strip from the supply preparatory to feeding the same to the die members, said means being pivotally supported for oscillating movement, and means for actuating the feed rolls and oscillatable strip-withdrawing means in timed relation to the reciprocable die member, said last mentioned means comprising a rotary crank operable by the die-reciprocating means and having a crank pin, a slide block journaled on said crank pin, a bar pivotally supported adjacent to one end and slidably engaged with said slide block so as to impart pivotal movement to said bar responsive to rotation of said crank, a rack pivotally connected with one end of said bar, ratchet and pawl means operable by said rack and establishing an intermittent drive with said feed rolls, and means interconnecting the bar with the oscillatable strip withdrawing means whereby to cause the latter to move in a direction to withdraw the strip from the supply source while the feed rolls are idle, and to move in the opposite direction as the feed rolls are driven to feed the withdrawn lengths of strip to the die members.

7. Apparatus as claimed in claim 6, wherein the interconnecting means between the pivotal bar and the oscillatable strip withdrawing means includes a yieldable connection.

8. In apparatus of the class described, which includes coactive die members, one of which is reciprocable towards and away from the other, and means for reciprocating the same, a source of strip supply positioned at one side of said die members, intermittently operable strip feeding means interposed between the source of strip supply and the die members, means positioned between the source of strip supply and the strip feeding means and about which the strip is adapted to be trained for withdrawing a length of the strip from the supply preparatory to feeding the same to the die members, said withdrawing means being pivotally mounted for oscillating movement, and means for oscillating the withdrawing means in timed relation to the reciprocable die member, said last named means comprising a rotary crank operable by the die-reciprocating means and having a crank pin, a slide block journaled on said crank pin, a bar pivotally supported and slidably engaged by said slide block, and means operatively connecting the pivotal bar with the oscillatable strip-withdrawing means whereby to impart oscillation to the latter responsive to the rotation of said crank.

9. In apparatus of the class described which includes coactive die members, one of which is movable towards and away from the other, and means for reciprocating said movable die member, a source of strip supply positioned at one side of said die members, strip feeding means adapted to engage said strip and positioned in advance of the die members for drawing said strip from the source of supply and for pushing the same towards the die members, means for imposing a drag upon the strip at the source of strip supply, means adapted to act upon the strip and positioned intermediate the source of strip supply and the strip feeding means for withdrawing a length of the strip from the source of supply, means for actuating said strip feeding means to advance the strip towards the dies after withdrawal of the length of the strip from the source of supply as aforesaid, said strip withdrawing and feeding means being intermittently operable in timed relation to each other and to the reciprocal movement of the movable die member, and means controlled by the strip for automatically discontinuing the motion of the reciprocal die member responsive to breakage of the strip.

10. The method of feeding foil strips to bottle cap making machines of the type which includes coactive relatively reciprocal cap blanking and forming dies, comprising applying to the strip

at a point adjacent to the dies, a clamping pressure, withdrawing a predetermined length of strip from a source of strip supply, thereafter advancing the strip by a pushing force applied to the same at a point intermediate the source of strip supply and the dies, and forming corrugations in the strip extending lengthwise of the strip adjacent to its opposite marginal edges during advancement of the strip from the source of strip supply to the dies.

11. In apparatus of the class described, which includes coactive die members, one of which is movable towards and away from the other, and means for reciprocating said movable die member, a source of strip supply positioned at one side of said die members, strip feeding means adapted to engage said strip and positioned in advance of the die members for drawing said strip from the source of supply and for pushing the same towards the die members, and means for intermittently actuating said strip feeding means in timed relation to the reciprocal movement of the movable die member, said last named means comprising pawl and ratchet means operatively connected with the strip feeding means, a rack and pinion means operatively connected with the pawl and ratchet means, a rotary crank operable in timed relation to the movable die member, a crank pin projecting laterally from said crank, and a slide block journaled on said crank pin and slidably mounted on a bar, the latter being pivotally supported at one end and having its opposite end operatively connected with the rack for actuating the latter and its pinion.

12. The method of making foil bottle caps and the like, which comprises intermittently withdrawing a length of foil strip from a source of strip supply positioned at one side of coactive relatively reciprocal cap blanking and forming dies, each intermittently withdrawn length being substantially equal to the diameter of a cap blank, intermittently advancing the strip between the dies by a pushing action after each withdrawing action, successively engaging the dies with the advanced end of the strip to successively cut circular blanks therefrom of a diameter at least as great as the width of the foil strip, thereby completely severing the advanced end of the foil strip and forming substantially triangular scrap pieces between successive blanks, and thereafter forming the blanks into finished cap form by means of the dies, and substantially simultaneously displacing the scrap pieces from the path of the strip and discharging the same separately from the finished caps.
